ABSTRACT OF THE DISCLOSURE

An apparatus for accurately applying edge ribbons to a continuous fabric strip of material which includes a pair of sensing devices for sensing the lateral positions of the edges of the strip material and mechanism for maintaining one of said edges of the strip material in registry with one of a pair of edge ribbon turnover devices and for maintaining the other edge ribbon turnover device in registry with the other edge of the strip material.

BACKGROUND OF THE INVENTION

This invention relates to means for enclosing the edge of strip material in a narrow folded strip of rubber, and has for an object to provide an improved apparatus for applying a thin strip of rubber to one, or both, of the lateral edges of strip material and for folding the strip rubber thereabout. In particular, the present invention relates to the binding of the edges of fabrics, such as low-angle bias-cut tire breaker fabrics as used in the construction of radial ply tires.

It is a further object of the present invention to provide an apparatus of the above type which evenly positions a binding ribbon of a relatively thin gum rubber over each marginal edge of such a continuous strip of low angle bias-cut tire breaker fabric.

It is a concomitant object of the present invention to provide an apparatus of the above type which is capable of applying the relatively thin gum rubber ribbons evenly to the opposite marginal edges of a continuous strip of bias-cut tire breaker fabric irrespective of width and/or lateral position variations of such fabric and even though the material is cut at a low bias-angle making it relatively weak at the edges thereof.

As an example of the use of the present invention there is illustrated an apparatus operating upon fabric strips which are used in the manufacture of pneumatic tire casings. The purpose of binding the strips is to "insulate" the edges thereof from the remaining portions of a tire carcass. This is customary practice in pneumatic tire manufacture. It is known, to splice together a series of bias-cut fabric strips so as to form a continuous length. It is also known to simultaneously therewith slice a wide strip of soft rubber stock into a plurality of strips, forming ribbons which are carried in continuous movement to the fabric to which they are attached by folding around the edges thereof. Such an arrangement is for example described in U.S. Pat. 2,060,269 issued on Nov. 10, 1936 to George F. Wikle.

With the advent of improved tire constructions, and particularly those using fabrics cut at low bias angles such as radial ply tires, the known edge applying apparatus has been found to be no longer satisfactory. Slight unavoidable variations in the lateral position of the continuous strip of fabric in moving through the apparatus and/or slight variations in the width of the fabric strip result, with the known apparatus, in non-uniformly applied edge ribbons. The purpose of the present invention is to provide an improved apparatus for binding a strip of fabric or other material, with a thin folded rubber ribbon, rapidly and economically and with uniformity as

2

to the width, thickness and relative position of the rubber edging. In binding strip material, such as fabric strip employed in the building of tire casings, with a folded edging of thin, unvulcanized sheet rubber ribbon stock, it has heretofore been the practice to apply the rubber with a pair of fixed folding fingers such as taught by the Wikle patent.

DESCRIPTION OF THE DRAWINGS

- 10 The foregoing objects and advantages will appear more fully in the following detailed description, when considered in connection with the accompanying drawings, in which:
15 FIG. 1 is a front elevational view of the apparatus according to the present invention;
FIG. 2 is a top plan view of the apparatus illustrated in FIG. 1;
FIG. 3 is a side elevational view of the apparatus in the direction of the arrows 3—3 of FIG. 1;
20 FIG. 4 is an end elevational view of the apparatus as viewed in the direction of the arrows 4—4 of FIG. 1;
FIG. 5 is a view taken in the direction of arrows 5—5 of FIG. 1 showing the fabric shifting means;
FIG. 6 is an enlarged front elevational, partly sectional, view of the fold over means according to the present invention;
25 FIG. 7 is a partial, partly sectional side elevational, view of the fold over means shown in FIG. 6;
FIG. 8 is a partial, partly sectional, top plan view of the fold over means shown in FIGS. 6 and 7;
FIG. 9 is a transverse sectional view of a fabric strip having edge insulating ribbons applied to the opposite edges thereof in accordance with the present invention; and
35 FIG. 10 is a perspective schematic view, enlarged with respect to the other figures, of the fold over blades in accordance with the present invention.

**DESCRIPTION OF THE PREFERRED
EMBODIMENTS**

40 Referring now to the drawings and first to FIG. 1, the present invention comprises a frame 1 rotatably supporting thereon a breaker fabric supply conveyor 10 for supplying a strip of breaker fabric 2. A conventional take-up spool 20 is journaled at the end of an arm 20a pivotally carried by frame 1. The spool 20 is maintained in tangential contact with a drum 25 journaled on frame 1 and driven by a conventional drive means such as an electric motor 25a connected thereto in conventional manner for 45 rotating the drum 25 in counterclockwise direction as viewed in FIG. 1 so as to advance the fabric 2 in the direction of the arrows. The conveyor 10 and the spool 20 are positioned at the same end of the apparatus but at different elevations with respect to each other. From the supply conveyor the fabric strip 2 is advanced along a generally U-shaped path, leading first to a fabric centering means 30 carried on frame 1 and then through an edge ribbon applicator means 50. Positioned on the frame 1 above the path of the fabric strip in the region of means 50, 50 is an edge ribbon supply and delivery means 40 for supplying a pair of ribbons to opposite edges of the fabric 2, as it advances toward the edge applicator means 50.

55 The fabric strip 2 being delivered by supply conveyor 10 whose speed is synchronized with that of drum 25 driven by drive motor 25a, passes initially under a guide roller 11 and from there over the first and under the second of a pair of parallel centering rolls 12 and 13 respectively, of the conventional centering means 30 as best seen in FIG. 5. As is known, the parallel rolls 12 and 13 are rotatably journaled between a pair of parallel plates 14 and 15 which later are, in turn, pivotally supported on movable blocks 14' and 15' respectively. The

blocks 14' and 15' are supported for movement along symmetrical, oppositely inclined, paths by means of the oppositely inclined symmetrical pairs of guide rods 17 and 18 which are affixed to the frame 1. A hydraulic actuator 19 parallel to the guide rods 17 is connected to the block 14' for movement of the block 14' along guide rods 17 to tilt the rollers 12 and 13. The parts are shown in FIG. 5 in their neutral, i.e. center position with the axes of rollers 12 and 13 perpendicular to the direction of fabric advance. The direction of actuation i.e. tilt of the rollers 12 and 13 may be controlled through suitable valves (not shown) which form part of a control means 16a which latter in turn is controlled by a pneumatic or photoelectric edge sensing head 16 of conventional design. The sensing head 16 is fixed to frame 1 adjacent the path of an edge *a* of fabric strip 2 and detects the position of said edge as the latter advances towards the edge ribbon applicator means 50, so as to keep said edge *a* in registry with a turnover blade 50a to be described in greater detail hereinafter. Whenever the edge *a* of fabric strip 2 shifts laterally with respect to the detector 16, the latter senses such shift in conventional manner and in response thereto actuates the control means 16a.

Whenever any lateral movement of the edge *a* of fabric strip 2 is detected by the sensing head 16 the actuating means 19 is actuated in a direction to tilt the rollers 12 and 13 angularly from the illustrated central position in either clockwise or counterclockwise direction depending upon the direction of lateral shift detected by head 16, so as to urge the strip 2 therebetween to shift laterally until edge *a* thereof is back in its predetermined position in registry with blade 50a. The centering means 30 and the operation thereof is known to those skilled in the art and is not therefore described in greater detail herein.

The fabric strip 2 is thus maintained in a position in which its edge *a* remains in registry with the blade 50a as hereinafter described in more detail. It will be apparent to those skilled in the art that alternatively other known means may be employed to detect lateral shifting of edge *a* of strip 2 and to maintain the latter edge in registry with blade 50a.

After leaving the centering means 30 the fabric strip 2 passes vertically to a guide roller 31 which deflects the strip into a horizontal path to a pair of parallel, closely spaced horizontally disposed rollers 51a and 51b rotatably journaled in the frame 1. The fabric strip 2 passes over roller 51a then between the pair of rollers and under roller 51b. From there the strip proceeds in a substantially horizontal path to a further set of parallel rollers 51c and 51d (FIG. 8) also rotatably journaled in the frame 1.

Roller 51c is spaced from roller 51b and positioned at a lower elevation than the pair of rollers 51a and 51b. The elevation of roller 51c is such that the peripheral surface thereof is located below and substantially tangent to a horizontal plane which in turn is located below and substantially tangent to the peripheral surfaces of the rollers 51a and 51b so that the fabric strip 2 will be guided along a substantially horizontal path intermediate the spaced rollers 51b and 51c.

After passing over roller 51c and then downwardly between rollers 51c and 51d and under roller 51d, the fabric strip 2 passes under an additional parallelly disposed guide roller 51e and thence over the drum 25 onto take-up spool 20.

The rollers 51a through 51d form part of an edge strip applicator means 50 for applying edge ribbons 3a and 3b (FIG. 9) to the respective edges *a* and *b* of fabric strip 2 so as to form a strip assembly 4, as will be described in more detail hereinbelow. After passing under roller 51e the strip assembly 4 passes over the surface of drum 25 from which it is wound onto spool 20 together with a liner 4a which is simultaneously unwound from a liner supply spool 5 conveniently journaled on frame 1.

As best shown in FIG. 3 there is provided a gum edge-

ribbon supply roller 41 for supplying a continuous strip of the gum material 3.

In order to gauge properly the width of the narrow ribbons of rubber 3a and 3b, there is provided a slitting unit which comprises a hard surface roller 42 mounted in bearings attached to the frame 1. This roller 42 is driven preferably through a chain drive by a suitable electric motor. A plurality of cutter discs 43 are positioned above the roller 42 in a manner to press with force against the surface of roller 42 so as to slice into narrower strips the wider strip 3 passing therebetween.

After passing over a portion of the surface of a further roller 45, also rotatably supported on frame 1 parallel to and having a positive drive connection with the roller 42, the ribbons 3a and 3b are independently withdrawn from the roller 45 by a pair of horizontally spaced parallel rollers 46a and 46b, respectively.

Roller 46a is rotatably journaled in fixed position in frame 1 while the roller 46b is rotatably journaled in a bracket 47 which is slidably carried on frame 1 for horizontal movement in directions toward and away from roller 46a, i.e., in directions to the left and the right as viewed in FIG. 3. The axes of rotation of rollers 46a and 46b are preferably located in a common horizontal plane, at an elevation above the edge ribbon applicator means 50, which will now be described.

The ribbon applicator means 50 includes a pair of parallel turnover blades 50a and 50b (FIG. 8) positioned alongside the marginal edges *a* and *b*, respectively, of the fabric strip 2.

The blade 50a is fixed to a pair of brackets 58' which in turn are rigidly connected to frame 1, so that blade 50a is stationary with respect to frame 1. Parallel to and horizontally spaced from blade 50a is a second blade, 35 namely blade 50b, fixedly connected to bracket 47 and movable with said bracket in directions toward and away from blade 50a in the horizontal plane defined by said pair of blades. A horizontal guide surface for guiding the fabric strip 2 between the blades 50a and 50b, and 40 in a direction parallel thereto, is defined by the upper horizontal surfaces of a pair of fixed parallel blocks 52a and 52b adjacent the blade 50a and a third parallel block 52c which is fixed to and movable with the bracket 47. The blades 50a and 50b include a horizontally elongated vertical wall portions 50a' 50b' respectively, and horizontally elongated curved lips 50a'' and 50b'' respectively depending from said wall portions (FIG. 10). The curvature of the lip portions 50a'' and 50b'' is such as to make the blades left hand and right hand blades respectively. 45 As best seen in FIG. 10 each of the lips 50a'' and 50b'' has a smooth, curved, guide surface which faces downwardly at the upstream end of the blade and upwardly at the downstream end and having a smooth transition in between. These guide surfaces have upstream end regions located in a substantially horizontal plane and curving toward the central region of the blade where they become substantially vertical, thereafter curving further until in the downstream region of the blade the guide surfaces once more become substantially horizontal but now face upwardly. The upstream regions of the lips 50a'' and 50b'' extend in opposite directions away from each other, and each of these lips curves inwardly until at their downstream regions the latter extend toward each other in a common horizontal plane. The construction of blades 50a and 50b is preferably such that the said upstream and downstream regions of the lips 50a' and 50b' are located substantially in the same horizontal plane.

The upwardly facing horizontal guide surfaces of fixed blocks 52a, 52b and of movable block 52c are preferably located in the same horizontal plane as the upwardly facing guide surfaces of the blades 50a and 50b respectively.

The result is a flexing of the marginal edges *a* and *b* 75 of strip 2 during its passage through blades 50a and 50b

in a manner to increase the pressure exerted by the lips 50a" and 50b" on the bent over portions of ribbons 3a and 3b so as to assure precise adherence of the ribbons to the strip.

The sensing head 16 is fixed laterally in a position in which it will detect variation in strip edge positions out of a path which is in registry with the inwardly facing surface of the vertical wall portion 50a' of blade 50a, so that the centering means 30 will keep the edge a of the continuous fabric strip 2 in substantial registry with the blade 50a. The ribbon delivery means 40 is arranged such that a vertical plane tangent to the surface of roller 46a on the side thereof which faces roller 46b, is in substantial alignment with said path of edge a. The gum ribbon 3a, therefore, leaves roller 46a in a path located in said vertical plane. The ribbon 3a is thereafter twisted 90° to permit it to pass over transversely positioned roller 51b which latter deflects the ribbon 3a into a horizontal direction i.e., superimposed on strip 2.

Carried on the movable bracket 47 is a second edge sensing detector 48 of conventional design. The detector 48 is positioned adjacent the marginal edge b of the fabric strip 2 for detecting the position of the latter edge. The signals from the detector 48 are fed by conventional means to a conventional control device 48a which controls the operation of a pair of valves which in turn, in known manner, control the direction of movement of the piston 49a reciprocably received in the hydraulic cylinder 49b which is suitably fixed to frame 1. Piston 49a, in turn, is rigidly connected to the bracket 47, thus completing a feedback for continuously urging the bracket 47 and the guide roller 46b, and the edge detector 48, mounted thereon, to remain in registry with the marginal edge b of strip 2. The inwardly facing vertical surface of wall 50b' of blade 50b is also located substantially in registry with detector 48. The latter is of course positioned in substantial alignment with the vertical plane which is tangent to the peripheral surface of roller 46b at the side thereof which faces away from roller 46a. Thus, the ribbon 3b which passes over roller 46b is deflected downwardly thereby along said vertical plane and then is twisted 90° into contact with the roller 51b which further deflects the ribbon 3b onto the horizontal strip 2. Thus, the cylinder-piston arrangement 49a and 49b moves the bracket 47 as a unit with the detector 48, the blade 50b, and the guide roller 46b so as to keep the blade 50b in substantial registry with the marginal edge b of the fabric strip 2. A suitable guide rod 49c and conventional guide rails 49d and 49e are provided for supporting the bracket 47 for said lateral movement thereof.

The ribbon guide rollers 46a and 46b, therefore, position the ribbons 3a and 3b, respectively, in proper overlapping relation with the edges a and b, respectively, of the fabric strip 2. The roller 51b (FIG. 6) operates to press the ribbons in proper adhesion with the edges of the fabric 2. The ribbons 3a and 3b are deflected respectively around the roller 51b, being sandwiched intermediate the roller and the respective marginal edge of the fabric strip 2, which latter is also deflected thereabout. The turnover blades 50a and 50b interposed between the rollers 51b and 51c are always positioned in substantial registry with the corresponding edges of the fabric strip 2 (FIGS. 7 and 8) and operate to turn the overlapping ribbons down and around the respective edges of the fabric strip 2. Following the turnover operation, the rollers 51c and 51d, by pressing against opposite faces of the folded edging ribbons, complete the stitching operation thereof, so that the ribbons 3a and 3b are securely adhered to both surfaces bordering the edges of the fabric 2.

In the preferred embodiment of the present invention the opposing inwardly facing surfaces of vertical walls 50a' and 50b' are slightly offset toward each other, each

with respect to its corresponding edge sensing means 16 and 48. The resulting spacing between the said opposing blade surfaces is preferably somewhat less than the width of a strip 2 passing therebetween resulting in substantial lateral pressures exerted on the ribbons 3a and 3b during folding thereof over the edges a and b of strips 2. In this manner a straight, tight fold is obtained which permits accurate alignment of the breaker strip with a tire carcass during a later operation.

As best shown in FIGS. 1 and 4, the rollers 42, 45 and 46a and 46b are driven in synchronism with the movement of the fabric i.e., with the rollers 51a through 51d.

The drive sprocket and chains for driving the rollers 42, 45, 46a and 46b in synchronism with each other, and with the fabric advance mechanism comprising the drum 25, are of conventional design. The roller 46b is, as noted above, movable toward and away from roller 46a and must therefore be driven by a drive mechanism which will permit such relative movement while maintaining the pair of rollers in synchronism with each other. Any suitable drive mechanism for accomplishing this purpose may be used such as for example the mechanism illustrated in FIG. 4, where a drive chain 60 interconnects all of the various sprockets associated with the rollers 42, 45, 46a and 46b so that when roller 45 is driven by a second drive chain 61, suitably connected by intermediate sprocket and chain drives to the motor 25a which also drives drum 25, the rollers 42, 45, 46a and 46b will also be driven in synchronism therewith. The aforesaid drive mechanism includes a suitable spring biased sprocket 62 for maintaining the chain 60 in driving connection with the various sprockets for all lateral positions of the roller 46b.

It will be seen that in accordance with the present invention the continuous fabric strip 2 and the pairs of ribbons 3a and 3b are assembled together (FIG. 9) in a manner wherein the ribbons are laid in accurately overlapped relation with the edges of the fabric strip and subsequently folded around said edges so as to completely uniformly enclose the edges of the fabric strip irrespective of width and lateral position variation of the latter. The edge a of fabric strip 2 is maintained in substantial registry with the turnover blade 50a while the turnover blade 50b is maintained in substantial registry with the edge b of the fabric strip 2. The gum ribbons 3a and 3b are adhesively applied in overlapping relation to the respective marginal portions of the fabric strip as the latter passes under the roller 51b (FIG. 6). The free margins of the gum strips are then turned inwardly under the fabric strip and are caused to adhere to the undersurface of said strip as the strip progresses between the turnover blades 50a and 50b. The unvulcanized rubber compound of the gum ribbons is tacky and therefore adheres readily to the fabric strip 2. Advancing downstream of the turnover blades 50a and 50b the now assembled strip 4 then passes over the wide roller 51c and then under roller 51d to perfect the adhesion of the ribbons to the strip. The completed strip assembly 4 is finally rolled up on spool 20 together with a liner 4a, after having passed over the drum 25. The take-up spool 20 is carried on a pivotally mounted arm 20a and urged, as a result of its own weight, into tangential contact with the drum 25 so as to insure a smooth transfer of the strip assembly 4.

In operation, a suitable drive motor 25a (FIG. 1) positively drives, via a suitable chain or timing belt transmission, the edge ribbon supply and applicator means in synchronism with the fabric strip advance means in a manner which will be apparent to those skilled in the art. After the fabric strip 2 has been initially threaded through the apparatus and applied to the wind-up spool 20, and the gum ribbon 3 from the free-wheeling supply spool 41 has been threaded through the cutting assembly 42, 43 and from there, in cut form, i.e. ribbons 3a and 3b, around the rollers 45, 46a, and 46b and thence over the

roller 51b into adhesive contact with the spaced edges of the fabric strip 2, the electric drive motor 25a is energized so as to positively drive the drum 25 for advancing the fabric strip 2 through the apparatus.

The fabric strip 2 is advanced through the apparatus in the direction of the arrows (FIG. 1), over the freely rotatable rollers 11, 12, 13, 19e, and 51a, b, c, d, and e. The fabric supply conveyor 10 is suitable driven in synchronism with the drum 25 by a conventional chain drive also connected to motor 25a. The rollers 42, 45, 46a and 46b are, of course, also driven in synchronism with the fabric advance means, by the motor 25a, so that the gum edge ribbons 3a and 3b will be advanced at the same rate of speed as the fabric strip 2. Meanwhile, the marginal scrap strips 3a' and 3b' of the cut edging material 3 are advanced, by means of driven rollers 44a and 44b respectively (FIG. 3) over a pair of inclined idler rollers 65 and 66 (only one of which is shown) which deflect the latter scrap strips out of the path of the cut edging ribbons 3a and 3b under a spring biased rubber-tired wheel 67 to a scrap receptacle (not shown) together with the liner 41a from ribbon supply spool 41.

In passing under a portion of the roller 51b the edging ribbons 3a and 3b are applied in overlapping relationship to the corresponding edges a and b of the fabric strip 2 which also passes under the roller 51b in contact with the underside of the edging strips. With the edging ribbons in this overlying relationship (FIG. 7) they continue to pass, together with the fabric 2, through the opposing turnover blades 50a and 50b, the surfaces 50a'' and 50b'' of which deflect the outwardly extending free portions of the ribbons 3a and 3b first downwardly around the respective edges a and b of the fabric and then upwardly into contact with the underside of the respective marginal edge portions of the fabric 2, adhering the deflected strip portions to such underside. After passing over and under, respectively, the idler rollers 51c and 51d the strip assembly 4 then passes under idler roller 51e and onto the surface of drum 25 with which the wind-up spool 20 is in pressure contact. It will be seen that lateral variations in positions of the edges a and b of fabric strip 2 are compensated for by movement of the fabric with respect to blade 50a and movement of the blade 50b with respect to the fabric, respectively. In this manner accurate application of the thin rubber ribbons 3a and 3b in accurately overlapping relationship to the fabric strip edges is accomplished.

It will be understood by those skilled in the art that suitable conventional electrical and fluid circuits will be employed in the foregoing tire building machine to automatically or manually regulate the various movements of the various parts of the machine as well as to synchronize the operations of the various components of the machine with respect to one another.

While particular embodiments of this invention have been shown and described it will be obvious to those skilled in the art that various changes and modifications may be made without departing from this invention in its broader aspects, and it is, therefore, intended in the appended claims to cover all such changes and modifications as fall within the true spirit and scope of the invention.

Having thus described the invention, what is claimed as new and desired to be secured by Letters Patent is:

1. In an apparatus for operating on a longitudinally advancing web, in combination:

first detector means for sensing lateral displacement, out of a given fixed path, of one edge of the advancing web;
web shifting means responsive to said first detector means for shifting the web laterally so as to maintain said one web edge in registry with said given path; movable operating means laterally spaced from said given path and adapted to operate on the other edge of said web;

second detector means for sensing lateral displacement of said other edge of said web; and means responsive to said second detector means for laterally shifting said movable operating means into continuous registry with said other web edge.

2. The apparatus according to claim 1, further comprising fixed operating means located adjacent said given fixed path for operating on said one edge of the advancing web.

3. The apparatus according to claim 2 wherein said fixed operating means comprises fixed applicator means for applying a binding ribbon in lapped relation to said one edge of said web and fixed folding means positioned downstream of said fixed applicator means for folding said binding ribbon around said one edge.

4. The apparatus according to claim 1 wherein said movable operating means comprises movable applicator means for applying a binding ribbon in lapped relation to said other edge of said web and movable folding means located downstream of said applicator means for folding said binding ribbon around said other web edge.

5. The apparatus according to claim 4, wherein said movable operating means comprises a movable member, said movable applicator means and said movable folding means being supported on, for movement with, said movable member.

6. The apparatus according to claim 1 further comprising fixed applicator means for applying a first binding ribbon in lapped relation to said one edge of the web; fixed folding means positioned adjacent said one edge of said web for folding said one binding ribbon therearound;

said web shifting means adapted to maintain said one edge of said web in substantial registry with said fixed folding means while said web is advanced; said movable operating means including movable applicator means for applying a second binding ribbon in lapped relation to the other edge of the web, and movable folding means for folding said second binding ribbon around said other edge;

said movable operating means responsive to said second detector means for maintaining said movable applicator means and said movable folding means in substantial registry with said other edge of said web;

whereby both said binding ribbons are accurately applied to the respective edges of the web irrespective of variations in the lateral position of the web or variations in the width of the web.

7. The apparatus according to claim 6 wherein said second detector means is movably supported and is adapted to automatically move laterally in response to variations in the lateral position of said other edge of the strip material so as to remain in substantial registry with said other edge.

8. The apparatus according to claim 6 further comprising means for separating both said binding ribbons from a single wider strip of rubber.

9. The apparatus according to claim 8 wherein said fixed and movable ribbon applicator means comprise respectively a first fixed and a second movable ribbon guide roller respectively supported for rotation about a pair of substantially parallel spaced axes located respectively in the regions of and extending substantially parallel to the opposite edges of said strip material.

10. The apparatus according to claim 9 comprising frame means, feed means carried by said frame means for advancing the web in a given direction, a member movably supported on said frame means for movement in direction transverse to said given direction, said movable folding means carried by said member for movement therewith in said directions transverse to said given direction; said first roller being fixed to said frame means

and said second roller carried by said movable member for movement together with said movable folding means.

11. The apparatus according to claim 10 further comprising a pair of parallel strip guide rollers supported on said frame means for rotation about axes transverse to said given direction, and said strip guide rollers being adapted to engage the opposite faces of said web, said ribbon guide rollers cooperating with one of said strip guide rollers for guiding the binding ribbons thereto in spaced relation to each other intermediate the surface of said one strip guide roller and the face of said strip material engaged thereby and in lapped relation to the respective marginal edges of said web.
